BALANCE RING FOR PULSATING FLUID MACHINERY

James O. Byers, Jr., Oakville, Conn., assignor to The Bendix Corporation, St. Joseph, Mich., a corporation of Delaware

Continuation of abandoned application Ser. No. 719,285, Mar. 5, 1958. This application Dec. 23, 1961, Ser. No. 162,877

1 Claim. (Cl. 103—161)

The present invention relates to rotating fluid handling devices having two parts which rotate relative to each other and which have end surfaces through which the axis of rotation passes and which are forced apart by fluid pressure forces; and more particularly to fluid pressure actuated balancing means for holding sliding sealing valving surfaces formed on the end surfaces of two relatively rotating parts into engagement with each other with a generally predetermined force. The present application is a continuation of U.S. application Serial No. 719,285 filed March 5, 1958, now abandoned.

The present invention has particular advantages in positive displacement hydraulic pumps and motors of the type having a casing member and an internal member which are relatively rotatable about an axis which passes through abutting end valving surfaces on the respective members, and which valving surfaces are biased apart by pressure of the fluid passing through the valving surfaces. In the usual design of pumps and motors of this type, the internal member is usually made the rotating member and is provided with a plurality of radially extending cylinders having pistons therein which reciprocate when the internal member is rotated. In such an arrangement fluid is usually added to and exhausted from the rotor, through ports in the end valving face of the rotor, as these rotor ports are rotated past suction and discharge ports in an abutting valving surface of the casing member. It is inherent in such an arrangement that fluid pressure from the discharge ports flows between the valving surface to bias the valving surfaces apart. An opposing force must therefore be applied between the rotor and casing members in order to hold the valving surfaces into sliding sealing engagement with each other.

It is highly impractical to manufacture rotors with an end to end dimension that provides a suitable sealing fit between two opposite end internal casing surfaces. Prior art attempts to produce pumps of this nature, and with which applicant is familiar, have utilized a plurality of slipper pistons which are biased outwardly of the rotor member into abutment with one inside face of the casing member to force the other face of the rotor member into sealing engagement with the opposite internal face of the casing member. Individual ones of these pistons have been communicated with individual ones of the pumping chambers in the rotor, so that the changing pressure in each pumping chamber will automatically change the force biasing the sealing surfaces together in a manner slightly greater but proportional to the force tending to separate the valving surfaces. Prior art structures have been quite complicated and expensive to manufacture, and what is more important have necessitated the expenditure of considerable power loss in rotating the plurality of individual slipper pistons over their abutting bearing surface.

An object of the present invention is the provision of a new and improved fluid handling device of the character above referred to which is greatly simplified in its construction, which is more efficient in its operation, and is cheaper to manufacture than prior art structures.

Another object of the present invention is the provision of a new and improved pump and/or motor of the above described type whose mechanical efficiency is considerably improved over prior art structures.

2

The invention resides in certain constructions and combinations and arrangements of parts; and further objects and advantages will become apparent to those skilled in the art to which the invention relates from the following description of the preferred embodiment described with reference to the accompanying drawings forming a part of this specification, and in which:

FIGURE 1 is a cross sectional view taken approximately on the line 1—1 of FIGURE 3 of a hydraulic pump embodying principles of the present invention;

FIGURE 2 is a cross sectional view taken approximately on the line 2—2 of FIGURE 1;

FIGURE 3 is an end view of the pump shown in FIGURE 1 having parts broken away and sectioned and is taken approximately upon the line 3—3 of FIGURE 1;

FIGURE 4 is an end view of a porting plate shown in FIGURES 1 and 2; and

FIGURE 5 is a cross sectional view taken approximately on the line 5—5 of FIGURE 4.

While the invention may be otherwise embodied, it is herein shown and described as embodied in a positive displacement hydraulic pump capable of producing pressures in the neighborhood of approximately 1,500 p.s.i. The pump is intended for use in the central hydraulic systems of farm tractors and the like.

The pump shown in the drawing generally comprises an outer casing member A having an internal chamber 10 therein containing a radially inwardly facing annular camming surface 12; and an inner member B having a plurality of radially outwardly extending cylinder bores 14 in which individual pistons 16 are positioned in a manner to be reciprocated by the camming surface 12 during relative rotation of the inner and outer members. The casing member in the present instance is a stationary one, and the internal member B is adapted to be rotated relative to the camming surface 12 by an axially positioned shaft 18 which extends through one end wall 20 of the casing member A. The inner end of the shaft 18 is journaled in a sleeve bearing 22 that is supported in an axial bore 24 in the opposite end wall 26 of the casing member A; and the projecting end of the shaft 18 is suitably journaled and sealed with respect to the end wall 20. The center portion of the shaft is suitable splined to the inner rotor member B substantially on the radial plane passing through the cylinder bores 14.

Each of the individual pistons 16 are provided with a ball 28 for engagement with the camming surface 12; and upon rotation of the shaft 18, centrifugal force causes the individual pistons 16 to be biased radially outwardly into firm engagement with the camming surface 12. Relative rotation between the inner and outer members causes the pistons 16 (of which there are 6 in the present pump) to be reciprocated in their cylinder bores 14. By properly communicating each cylinder bore 14 to a supply of fluid at suction pressure when its piston 16 is moving radially outwardly, and by properly communicating each cylinder bore to the discharge passages of the pump when its piston 16 is moving radially inwardly, a pumping action is established. By successively valving each of the cylinder bores 60 to the suction and discharge connections of the pump during their respective suction and discharge strokes, a continuous flow of fluid is achieved.

Inasmuch as the position and duration of the suction and discharge strokes for each cylinder are fixed by the configuration of the camming surface 12; and inasmuch as the camming surface is held stationary with respect to the casing member A, the start of the suction stroke for each cylinder will take place when each cylinder moves into precisely the same position relative to the casing member A, and will continue over precisely the same circular arc of the casing member. Likewise, the discharge stroke for each cylinder starts when each moves

into precisely the same position and continues over the same circular arc of the casing member. Fluid can be added to and taken from each of the individual cylinders to suction and discharge passages in the casing member when the cylinders are properly positioned in the housing member relative to the camming surface 12.

The pump shown in the drawing has a generally elliptically shaped camming surface 12, so that each individual cylinder has two pumping cycles during each revolution of the rotor member B. Valving of each individual pumping cylinder to the suction and discharge connections of the pump is accomplished by a rotary disc valve arrangement formed between one end of the rotor member B and the end wall 26 of the casing member A. The rotary disc valve arrangement shown generally comprises a pair of matching valving surfaces which slidably sealingly engage each other, and one of which surfaces 30 is formed in and rotated by the rotor member B while the other valving surface 32 is supported on the casing member A. In order that sealing angular alignment of these surfaces can be accomplished easily when the pumps are made on a mass production basis, the matching valving surfaces 30 and 32 are spherically shaped; and in order that the valving operation can be adjusted relative to the camming surface to vary the discharge of the pump (as will later be described), the valving surface 32 is formed as a surface of a port plate 36 which can be angularly positioned relative to the casing member A.

The pump shown in the drawing is intended to handle an oil having considerable lubricating qualities, and has been designed to permit fluid from the suctioned connection 38 of the pump to be distributed through an annular groove 40 in the end wall 26 to the internal chamber 10 of the pump. The valving surface 30 of the rotor member B is provided with a plurality of identically shaped circular ports 42 each of which communicate with a respective cylinder bore 14; and these ports 42 are uncovered by the port plate 36 to permit fluid from the internal chamber 10 to be drawn into the cylinder bores during their suction strokes. The ports 42 must, therefore, be sealed off from the internal chamber 10 during their discharge strokes; and inasmuch as the camming surface 12 causes these discharge strokes to be produced over two diametrically opposite 90° arcs, the port plate 36 has an "hour glass type" of configuration, as best seen in FIGURES 2 and 4, capable of sealing off the ports 42 from the internal chamber 10 over two diametrically opposite 90° arcs.

Referring now to FIGURE 2 of the drawings, the port plate 36 is shown therein in its position providing maximum displacement for the pump. Assuming counter clockwise rotor rotation as seen in FIGURE 2, the pistons 16 start their discharge strokes when the center line of their cylinder bores 14 become coincident with the major axis 44 of the camming surface. When the center line of the ports 42 become coincident with the major axis 44, the trailing edge of the ports 42 become coincident with the leading edge 46 of the leading sealing surface 48 of each half of the port plate's valving surface 32, and the ports 42 become sealed off from both the suction and discharge connections of the pump for the following approximately 3° of rotor rotation. Approximately 3° of rotor rotation after the cylinder bores 14 pass the major axis 44, the leading edge of the circular ports 42 become coincident with the leading edge 50 of an arcuately shaped discharge port 52 that is centrally positioned within each half of the port plate 36. Thereafter subsequent rotation of the rotor member causes the circular ports to start the opening operation of the discharge ports 52 which continues for approximately 32° of rotor rotation. The leading edge 50 and the trailing edge 54 of the discharge ports 52 are formed to the same radius as the circular ports 42, and about centers which are spaced 23° of rotation apart so that the circular ports 42 remain full open with respect to the discharge port 52 for the next approximately 23°

5 of rotation. Thereafter the leading edge of the circular ports 42 begin to move past the trailing edge 54 of the discharge port 52; and after approximately 32° of further rotation, the trailing edge of the circular ports 42 become coincident with the trailing edge of the arcuately shaped discharge port 52 to close off the ports 42 from both the suction and discharge of the pump. This occurs as the center lines of the individual cylinder bores 14 become coincident with the minor axis 56 of the camming surface 12; and the circular ports 42 are valved off from both the suction and discharge of the pump thereafter for approximately 3° of rotor rotation.

10 The leading edge of the ports 42 become coincident with the trailing edge 58 of the trailing portion 60 of the valving surface 32 after the cylinder bores 14 have moved approximately 3° past the minor axis 56 of the camming surface 12; and the individual circular port 42 will remain in communication with the internal chamber 10 or suction passages of the pump until the trailing edge 46 of the ports 42 become coincident with the leading edge 15 20 of the other half of the valving surface 32—which occurs when the center line of the cylinder bores 14 become coincident with the major axis 44. This completes one suction and discharge cycle as occurs over 180° of rotor rotation; and thereafter the cycle is repeated with respect to the other half of the porting plate 36 during the second 180° of rotor rotation.

25 The port plate 36 slidably sealingly engages a planar surface 62 in the end wall 26 of the casing member A in which are located a pair of diametrically opposed discharge ports 64 with which the arcuately shaped discharge ports 52 of the porting plate always communicate. The ports 64 are formed by longitudinally drilled passageways 66 which are intersected by a transverse drilling 68 which in turn is intersected by the discharge port 70 of the pump.

30 As previously indicated the port plate 36 is made arcuately movable in order that the pump's displacement, or quantity of fluid which will be delivered the pump 40 during one revolution of the rotor, might be varied. By rotating the port plate 36 in a clockwise direction from the position shown in FIGURE 2, the individual circular ports 42 will be valved off by the leading portion 48 of the valving surface 32 prior to the time that the radially outward stroke of the individual pistons 16 have been completed; so that only a fraction of each cylinder bore's maximum displacement is filled with fluid from the inlet of the pump. The individual circular ports 42 will thereafter be valved off from both the suction and discharge connections of the pump for approximately 3° of rotor rotation; and thereafter the individual circular ports 42 will be connected with the arcuately shaped discharge port 52 in the port plate 36 so that fluid will be taken into each cylinder from the discharge of the pump for the remainder 45 of each piston's suction stroke. Inasmuch as the port plate 36 is proportioned to connect the individual circular ports 42 to the discharge of the pump for approximately 87° of rotor rotation, movement of the center line of the cylinder bores 14 past the major axis 44 of the camming surface causes fluid to be forced out through the discharge ports 52 and 64. Discharge through these ports continues past the major axis 44 through an angular displacement of the remainder of 87° of rotation, which will now terminate before the cylinder bores 14 reach the minor axis 56. Thereafter the ports 42 will be valved off from both the suction and the discharge of the pump 50 for approximately 3°; and will then be communicated with the suction of the pump during the remaining portion 55 of the discharge stroke of the individual pistons 16. It will therefore be seen that by angularly displacing the porting plate 36, part of the suction stroke for each cylinder bore 14 will be taken up with fluid obtained from the discharge ports of the pump; and a corresponding fluid displacement of the discharge stroke for each cylinder bore 14 will be passed to the suction of the pump. By this 60 65 70 75

expediency the total quantity of fluid passing the outlet of the pump per rotor revolution can be varied or controlled by adjusting the angular position of the porting plate 36 relative to the camming surface 12.

The pump shown in the drawing is provided with automatic means for angularly positioning the port plate 36 in a direction decreasing the displacement of the pump when the pressure in its discharge passages exceeds a predetermined pressure, which in the present instance is approximately 1,500 p.s.i. The automatic means C for positioning the port plate is best seen in FIGURE 3 of the drawings; and generally comprises a cylindrically shaped slide member 72 which is positioned in a transverse bore 74 in the cover plate 26. The slide member 72 is notched out as at 76 to receive a pin 78 that extends through an arcuately shaped opening 80 within the cover plate 26 that communicates the bore 74 with the back of the port plate 36. Pin 78 is rigidly connected to the port plate 36; and the port plate 36 is held in its maximum displacement producing position, shown in FIGURE 2, when the inner end of the slide member 72 is held into engagement with a shoulder 82 formed on the inner end of the transverse bore section 74. The slide 74 is held in this position by a coil spring 84 which is biased against an abutment plate 86 positioned against the outer end of the slide member 72 and a closure member 88 which is suitably held in place in the outer end of the transverse bore 74.

The slide member 72 is adapted to be rotated in a direction reducing the displacement of the pump by a piston 90 that is positioned in a smaller diameter bore section 92 in the bottom end of the bore 74; and which in turn is actuated by pressure supplied to its inner surface. Pressure actuation of the piston 90 in turn controlled by a slide valve structure 94 which is adapted to communicate the bottom end of the piston 90 to the suction pressure of the pump until such time as the discharge pressure of the pump reaches a predetermined level of approximately 1,500 p.s.i. Thereafter, the slide valve structure 94 is moved to modulate discharge pressure of the pump to the cylindrical piston 90 causing the slide member 72 to be moved outwardly compressing the spring 84 and moving the pin 78 in a direction decreasing the displacement of the pump.

The slide valve structure 94 is positioned in a bore 95 which intersects another small diameter bore 98 that communicates with the inner end of the bore section 92. The slide valve structure is provided with a pair of spaced lands 100 and 102 which when properly positioned will just straddle the bore 98 and close off the portions of the bore 95 which lie on opposite sides of the bore 98 from communication with the cylindrical piston 90. Pressure from the discharge passage 66 is fed through two intersecting bores 104 and 106 to the inner end portion of the bore 95. The outer portion of the bore 95 is communicated with the annular suction groove 40 by a longitudinal drilling 108; so that either suction or discharge pump pressures can be communicated to the cylindrical piston 90 depending upon the positioning of the slide valve structure 94. The slide valve structure 94 is biased inwardly to normally communicate suction pressure to the inner end of the cylindrical piston 90 by a coil spring 110 which normally holds an abutment plate 112 that is positioned against the end of the slide valve member 94 into engagement with the bottom end of the counterbore 116 in which the spring 110 is situated. The spring 110 is compressed a predetermined amount by a plug 118 which is forced into the outer end of the counterbore 116 and suitably held in place. When a predetermined pump discharge pressure, which in this instance is approximately 1,500 p.s.i. is delivered to the inner end of the bore 95 the slide valve structure 94 is biased outwardly against spring 110 to cause the abutment plate 112 to begin to move out of engagement with the bottom end 114 of the counterbore 116. This causes the land 102 to begin to throttle flow between the exhaust drilling 108 and the

inner end of the cylindrical piston 90; and inasmuch as some leakage always occurs past the lands 100 and 102 discharge pressure from the drilling 106 will flow past land 100 to the drilling 98. Inasmuch as outlet flow from the drilling 98 to the exhaust drilling 108 is now being throttled, a control pressure is established in the drilling 98 which will be of an intensity which depends upon the relative overlap being maintained with respect to the lands 100 and 102. A pump discharge pressure of approximately 1,650 p.s.i. pressure on the inner end of the slide valve 94 will cause the inner land 100 to be moved out of overlap with respect to the inner end of the bore 95, and sufficient pressure is delivered against the cylindrical piston 90 to move the port plate 36 into its "no flow" position. At pump discharge pressures between 1,500 p.s.i. and 1,650 p.s.i., a proportionate pressure is delivered against the cylindrical piston 90 to cause the port plate 36 to assume intermediate positions.

Pressure from the arcuately shaped discharge ports 52 in the port plate 36 will, of course, tend to flow through the space between the valving surfaces 30 and 32 and will tend to bias the valving surfaces apart. Should the surfaces become separated, discharge from the cylinder bores 14 will be short circuited directly to the internal chamber 10 thereby greatly decreasing the pump's hydraulic efficiency. The valving surfaces 30 and 32 must therefore be biased together by an amount of force which will prevent excessive leakage between the valving surfaces. In order that the pressure seepage between the valving surfaces might be confined to as small an area as possible, and thereby decrease the amount of force tending to bias the valving surfaces apart, an annular groove 120 is formed in the surface 30 a short distance radially outwardly from the radially outer edge of the arcuately shaped discharge ports 52. Similarly an axially positioned recess 122 is formed in the rotor member B with its radially outer edge positioned a short distance radially inwardly from the inner edge of the arcuate shaped discharge ports 52. It will therefore be seen that pressure forces upon the port plate are confined to its area bounded by the annular groove 120, the axially positioned recess 122 and its leading and trailing edges 46 and 58 respectively. A full discharge pressure will be exerted against the rotor member B on areas defined by the arcuately shaped discharge ports 52 and the pressure distribution on the remainder of the area bounded as previously set forth, will vary from substantially full pump discharge pressure adjacent the arcuate opening 52 to substantially suction pressure around the outer edges of the area previously set forth. An approximation of the force biasing the valving surfaces apart can be obtained by adding: the force obtained by multiplying the area which is in sliding sealing engagement by a pressure which is approximately one half of the difference between suction and discharge pressures, and the force obtained by multiplying full discharge pressure to the area of the arcuately shaped discharge ports plus the area of all circular ports 42 which are communicated to pressure.

According to principles of the present invention, the valving surfaces 30 and 32 are forced into sliding sealing engagement with each other with a generally predetermined force by a single annular balancing piston 124 which extends around the shaft 18. The annular piston 124 is preferably confined to an area that is as close as possible to the shaft 18; and in the embodiment shown in the drawing, is positioned in a counterbore 126 in the end of the opening in the rotor member B through which the shaft extends. O-ring seals 128 and 130 are provided between the annular piston 124 and the sidewalls of the counterbore and shaft respectively; and another O-ring seal 132 is provided in the shaft opening of the rotor member inwardly from the counterbore 126. The outer surface 134 of the annular piston 124 bears against an annular abutment or slipper plate 136 which is non-rotatably supported on the end wall 20 of the casing member

A surrounding the shaft 18. Fluid under discharge pressure is admitted to the inner surface of the annular piston 124 to force the annular piston into abutment with the slipper plate 136 to produce a reaction which holds the valving surface 30 of the rotor member B into sealing engagement with the valving surface 32 of the port plate 36. The cross sectional area of the annular piston 124 is preferably of such a size so as to at all times bias the valving surfaces 30 and 32 together by an amount sufficient to prevent excessive flow between the valving surfaces.

According to further principles of the present invention, pressure is supplied to the counterbore 126 from individual ones of the cylinder bores 14. Inasmuch as the pressure in these cylinder bores varies between suction and discharge pressures, a check valve is provided in these passages to prevent return flow from the counterbore to the cylinder bores during their suction strokes. In the embodiment shown, the interconnecting passageway 138 is counterbored as at 140 adjacent the bottom of the counterbore 126, and a ball 142 is positioned therein to prevent the return flow. The depth of the counterbore 140 is preferably just sufficient to provide from .005 to .010 of an inch clearance between the bottom of the counterbore, such that very little travel is required of the ball before it is brought into engagement with its seat.

In order to lubricate the sliding surface between the annular piston 124 and the slipper plate 136, a pair of concentric annular grooves 144 and 146 are provided in the outer surface 134 of the annular piston. Fluid under pressure from the counterbore 126 flows through a passageway 148 in the annular piston and then through a groove 150 in the surface 134 which extends between the recesses 144 and 146. The same pressure that is delivered against the inner edge of the annular piston 124 is therefore delivered to the sliding surface between the piston 124 and slipper plate 136 to relieve the mechanical bearing forces between these surfaces. The annular area between the grooves 144 and 146 is sized in such a way that the hydraulic forces tending to separate the annular piston 124 from the slipper plate 136 will at all times be slightly less than the force against the end of the annular piston 124 positioned in the counterbore 126; and as previously indicated the annular piston 124 is so sized as to hold the valving surfaces 30 and 32 together. Rotation of the annular piston 124 relative to the shaft 18 is prevented by a pin 152 which extends into aligned opening 154 and 156 in the piston 124 and rotor member B, respectively.

Describing now the operation of the pump with the porting plate 36 in its maximum flow producing position shown in FIGURE 2, fluid enters through the pump suction 38 to the annular groove 40 where it is distributed uniformly to the internal chamber 10 of the pump. With the port plate 36 in the position shown in FIGURE 2, the circular ports 42 in the rotor member B will be in communication with the internal chamber 10 for substantially the full suction stroke of their pistons 16, and until the center line of the bores 14 are coincident with the major axis 44 of the camming surface 12. The ports 42 are valved off from both the internal chamber 10 and the discharge port 52 for the next 3° of rotor rotation. At approximately 3° of rotation after the center line of the cylinder bores have passed the major axis 44, the circular ports 42 become communicated with the arcuately shaped discharge port 52 so that inward movement of the pistons 16 causes fluid to flow out through the ports 42, and the arcuately shaped discharge port 52 to one of the discharge ports 64 in the removable end wall 26 of the casing member. Inasmuch as the camming surface 12 is elliptically shaped to produce two pumping cycles during each revolution of the rotor member, flow simultaneously proceeds through both of the diametrically opposed drilled passageways 66 to the transverse drilling 68 and out through the discharge port 70 of the pump. When the center line of the cylinder bores 14 reach the minor axis 56 of the cam-

ming surface 12, the trailing edge of the circular ports 42 move out of engagement with the arcuately shaped discharge port 52 to valve off the cylinder bores 14 from both the suction and discharge connections of the pump. The ports 42 remain sealed off from both of the suction and discharge passages of the pump for the next 3° of rotation, or until their center lines have moved approximately 3° of rotation past the minor axis 56; and thereafter the leading edge of the circular ports 52 moves past the trailing edge 53 of the port plate 36 to establish communication with the suction of the pump. The ports 42 remain in communication with the pump suction for approximately 87° of rotation thereafter; and the entire cycle will thereafter be repeated with respect to the diametrically opposed portion of the port plate 36.

As previously indicated, the amount of fluid discharged from the pump can be varied or regulated by rotation of the port plate 36 with respect to the camming surface 12 of the casing member. Angular displacement of the port plate 36 with respect to the casing member A is accomplished by the structure best shown in FIGURE 3, and which comprises a slide member 72 that is normally biased into its maximum flow producing position by the coil spring 84. The slide 72 is caused to angularly displace the port plate 36 in a direction reducing the output of the pump when a pressure exceeding approximately 1,500 p.s.i. is supplied to the piston 90 which abuts the inner end of the slide member 72. When the discharge pressure of the pump exceeds approximately 1,500 p.s.i., the spool valve structure 94 moves outwardly to compress spring 110 sufficiently to cause land 102 to lap with respect to bore 96. Thereafter variable leakage rates pass the lands 100 and 102 causes increasing control pressure to be delivered against the piston 90 which in turn causes the slide 72 to compress spring 84 and rotate the port plate 36. The port plate 36 will be rotated by increasing amounts as the discharge pressure exceeds 1,500 p.s.i.; and when approximately 1,650 p.s.i. discharge pressure is reached, the slide member 72 will abut plug 88 and the port plate 36 will be rotated to its "no flow" producing position for the pump. As the discharge pressure of the pump falls below 1,650 p.s.i. the reverse operation is produced; and it will therefore be seen that the pump is capable of adjusting its rate output to correspond with the consumption of the hydraulic system to which it is connected. The precise manner in which angular displacement of the port plate 36 reduces the displacement of the pump has previously been set forth in detail and will not further be described.

During the discharge stroke of the cylinder bores 14, pressure fluid flows from individual ones of the cylinder bores 14, passes through the passageway 138, past the ball check 142 into the recess 140 to bias the annular piston 124 into engagement with the slipper plate 136. When the individual cylinders 14 become communicated with the internal chamber 10 of the pump, a slight reversal of flow causes the ball check 142 to engage its seat and thereby maintain pressure within the recess 122. As previously indicated, some of the fluid supplied to the recess 122 passes through passage 148 to the annular grooves 144 and 146 to pressurize the abutting surfaces of the annular piston 124 and slipper plate 136 to thereby reduce the direct bearing force between their sliding surfaces. As previously indicated the hydraulic force tending to separate the surfaces of the annular piston and slipper plate is less than the pressure force on the inner end of the annular piston biasing it into engagement with the slipper plate 136 and which force in turn is greater than the hydraulic pressure forces tending to separate the valving surfaces 30 and 32 by an amount preventing excessive flow therebetween. A continuing amount of leakage occurs out of the grooves 144 and 146, as well as past the O-rings 123, 130, and 132 which must be replaced by flow through passage 138 and check valve 142. In order that at least one flow passage 138 will at all times be communicated

to pressure, three of the cylinder bores 14 in the present instance are provided with these passage and check valve structures.

The balancing piston structure of the present invention is not only simpler than that of prior art structures employing individual balancing pistons one for each of the cylinder bores 14; but has proven to have a much greater mechanical efficiency, requiring considerably less horsepower to produce rotation of the rotor member B with respect to the casing member A. The single annular piston of the present invention greatly reduces the frictional forces between itself and its slipper plate; inasmuch as considerably less surface is swept by the singular annular piston of the present invention than is required to be swept by a plurality of individual circular pistons. What 15 is more, the effective moment arm through which these frictional resistances are exerted upon the shaft 13 is reduced to a practical minimum by the present invention. A further advantage is believed obtained by the single annular piston construction in that the fluid pressurized surface on the slipper plate 136 is maintained at all times by the single annular piston; while that in the prior art structures is constantly changing in a manner causing the pressure fluid to be swept from between the balancing pistons and the slipper plate which they abut.

It will be apparent that the objects heretofore enumerated as well as others have been achieved, and that an improved balancing piston arrangement has been provided for fluid devices having end valving surfaces which are biased apart by pressure fluid between the valving surfaces. While the invention has been described in considerable detail, I do not wish to be limited to the particular constructions shown and described, and it is my intention to cover hereby all novel adaptations, modifications and arrangements thereof which come within the practice of those skilled in the art to which the invention relates and which come within the scope of the following claim.

I claim:

In a hydro-mechanical device: a casing member having an internal chamber with opposite end walls through which an axis of rotation extends, a rotor mounted for rotation in said chamber about said axis, one of said end walls of said casing having a rotary valving surface with inlet and outlet ports therein, and the other of said end walls of said casing having a smooth abutment surface 45 thereon, one end of said rotor having a cooperating rotary

valving surface in sliding sealing engagement with said rotary valving surface of said casing, and the opposite end of said rotor having an axially positioned recess there-in opposite said smooth abutment surface on said casing, an annular balancing piston operatively connected to said rotor for rotary movement therewith and having an inner surface and an outer surface, said balancing piston being received in said recess and slidably and sealingly engaging the side of said recess for relative axial movement therebetween, the inner surface of said balancing piston being disposed within said recess and the outer surface thereof slidably engaging the smooth abutment surface of said casing, passage means communicating a portion of said outer surface with said inner surface whereby pressure in said recess will be communicated to said portion of said outer surface, a shaft rotatably mounted to the end walls of said casing for rotation about the axis, said shaft being operatively connected to said rotor for rotating the same and extending axially through said rotor, said recess and said balancing piston, said rotor having at least one expandible chamber which communicates with said rotary valving surfaces and which expands and contracts during rotation of said rotor, said rotor having a passageway communicating said annular recess with said expandible chamber, a valve seat in said last named passageway, a ball check valve member adapted to be seated on said seat, said ball valve being so arranged in said last named passageway to be unseated by pressure flow to said recess from said expandible chamber and to be seated by pressure in said recess to prevent reverse flow to said expandible chamber, whereby said pressure in said recess acts on said piston inner face to bias the outer face of said piston into sliding engagement with said smooth abutment surface and said rotor valving surface is biased against said casing valving surface by substantially constant pressure in said recess.
